UNITED STATES PATENT OFFICE.

CHARLES F. SMITH, OF NEW YORK, N. Y.

CLOTHES-LINE SUPPORT.

1,159,284.

Specification of Letters Patent.

Patented Nov. 2, 1915.

Application filed August 7, 1915. Serial No. 44,272.

To all whom it may concern:

Be it known that I, CHARLES F. SMITH, a citizen of the United States, and a resident of the city of New York, borough of Brooklyn, in the county of Kings and State of New York, have invented a new and Improved Clothes-Line Support, of which the following is a full, clear, and exact description.

10 This invention relates to clothes line supports and particularly to a support adapted to be arranged on a window frame and to be swung in and out through the window opening, and has for an object the provision of 15 an improved construction readily applied and readily removed and which may be utilized for supporting a single line or plural- ity of lines.

Another object of the invention is to apply 20 a hinged supporting device for a clothes line to the frame of a window and to so construct the device as to maintain the same tension on the line regardless of the position of the support.

25 A still further object in view is to provide a swinging clothes line support adapted to be swung through a window opening so as to extend into the interior of the building or be swung to an exterior position, and to 30 support a plurality of clothes lines in such a manner as to cause the lines to travel at the same speed and in the same direction.

In the accompanying drawings:—Figure 1 is a perspective view of an embodiment of 35 the invention, the same being shown applied; Fig. 2 is an enlarged fragmentary sectional view through Fig. 1 on line 2—2; Fig. 3 is an enlarged fragmentary sectional view through Fig. 1 on line 3—3; Fig. 4 is a perspective view of the invention shown in the 40 outer or folded position; Fig. 5 is a perspective view of a slightly modified form of the invention, the same being shown applied to a window frame.

45 In producing a device embodying the invention the same may be rearranged and the various parts changed without departing from the spirit of the invention, provided the principle involved is retained.

50 When the device is in position it is connected with the frame of a window and may be swung so as to extend through the window opening into the interior of the room so that clothes may be hung on either of the 55 lines and then the lines operated for moving the clothes out through the window opening.

The construction of the support is such that when all the clothes have been placed on the line the support, together with part of the line, may be swung outwardly through the 60 window opening and there secured in position in such a manner as to hold the lines taut.

The invention is applicable to either one, 65 two, or more lines but for the purpose of illustration only two forms are shown, namely, the construction for using two lines, as disclosed in Fig. 1, and the construction for using one line, as shown in Fig. 5.

Referring to the accompanying drawings 70 by numerals, and particularly to Fig. 1, 1 indicates a casing and 2 a window frame shown raised. Connected with the casing 1 is a block 3 to which is secured a holder 4 provided with a notch or opening for receiving the leaf 5 of hinge 6. The other leaf of the hinge 6 to leaf 5 is connected with a bar 7 in any suitable manner, said bar being also connected with a transverse bar 8 carrying pulleys 9 and 10. A suitable 75 aperture is provided in the holder 4 and also in leaf 5 so that the pin 10 may be thrust therethrough for locking these parts in position. A plurality of eyelets 11 are provided on block 3, the same being adapted 80 to receive the hook 12 when the parts are swung to an outer position, as shown in Fig. 4. The particular angle at which the bar 7 and associated parts may be positioned 85 is controlled by the particular eyelet 11 engaged by the hook 12. A hook 13 similar to hook 12 is provided on the opposite side of bar 7 and engages an eyelet of any suitable kind arranged interiorly of the casing 1 so as to hold the bar 7 in any desired position, preferably to hold the same so that 90 the outwardly traveling lines 14 and 15 may be an appreciable distance from the casing 1. Adjacent the lower part of the bar or plate 3 is arranged a pulley bar 16 carrying a pair 95 of superimposed pulleys 17 and also a pair of superimposed pulleys 18. Bar 16 is provided with a plate 16' (Fig. 2) which is bent at 16" for forming a hook member 19 adapted to be inserted into a slot or notch 100 in the plate 21. Plates or holders 4 and 21 are secured to the plate or bar 3 by suitable screws or other desired securing means. By the construction just described the pulley bar 16 may be readily applied and removed 105 at any time and also arm 7 may be applied and removed at any time, pin 10 of course

being disconnected. The pulleys 17 and 18 act as return guides for the clothes lines so that the return part of the line may be spaced apart from the outgoing sections of the lines 14 and 15. Connected with the post 22, which may be at any desired distance from the house, is an auxiliary pulley bar 23 carrying pairs of pulleys 24 and separate pulleys 25 and 26 spaced an appreciable distance apart so as to maintain the outgoing sections 14 and 15 a desired distance apart. The outgoing lines pass over pulleys 25-26 and from thence over pulleys 24 to pulleys 18 and then to pulley 17, after which they pass over the guide pulley 10 from which they extend to the inner pulleys 27 and 28. Pulley 27 is connected with a bracket 29 rigidly secured to bar 7, a suitable brace 30 being provided for reinforcing the bracket. Preferably the pulley 27 is connected with bracket 29 through an eyelet or hook whereby the pulley may be removed at any time. A pivotally mounted bracket 31 is connected with bar 7 by a pivotal pin 32 (Fig. 4). The bracket 31 is provided with an aperture or socket 33 and also with apertures at 90° angle therefrom on each side of bracket 31. These apertures are adapted to receive the pin 34, which pin extends through a suitable aperture in the metal reinforcing clip 35. When the bracket 31 is in the position shown in Figs. 1 and 5 pin 34 locks the same in that position, but if it should be desired to be swung through 90° , pin 35 would be removed and replaced when aperture 33 came opposite the pin. If it is desired to swing 180° from the position shown in Fig. 4, the pin 34 will be removed and replaced after having been moved said 180° . A hook 36 is connected with bracket 31 and is adapted to be inserted into the eyelet 37 connected with the pulley 38, whereby the pulley is removably mounted in position. When the line is being used and clothes are being secured to sections 14 and 15 thereof, the parts are in the position shown in Fig. 1. As the sections 14 and 15 are filled the same are gradually moved outwardly, these sections moving in unison as there is only one endless cable or line used. After all the clothes have been placed upon the line the inner part of the sections 14 and 15 are placed over the pulley 9, as shown in dotted lines in Fig. 1, and then hook 13 is disengaged from its eyelet, after which the parts are swung outwardly to the position shown in Fig. 4 where hook 12 is caused to engage one of the eyelets 11, thus locking the parts in their outer position without disturbing the tension on the line.

In Fig. 5 a slightly modified form of the invention is shown in order to adapt the device to a single line. In this form of the device the bracket 31 is arranged parallel with bracket 29 and the pulley 27 is connected

with bracket 29, while a suitable pulley 39 is connected in any suitable manner with the post or other support an appreciable distance away from the window. After the clothes have been placed in position the line 40 is moved to the position shown in Fig. 5 and then arm 7 is swung outwardly in a similar manner to the preferred form. The arm 7 may be of any length provided it is short enough to swing through the window opening. By providing this construction and arrangement the clothes may be placed on the line in the room and then moved out through the window opening without requiring the operator to lean out of the window. This arrangement is provided and associated with the pulleys for holding the line in its original position when the arm 7 is swung out of the window opening, thus maintaining the line taut.

What I claim is:

1. In a clothes line support of the character described, an arm adapted to be swung through a window opening, a pair of pulleys connected with the free end of said arm, a pair of pulleys arranged exteriorly of the window casing, a doubled clothes line passing over said pulleys, guiding means for guiding said clothes line in its return movement whereby the outwardly moving sections of the clothes line will move at the same rate of speed and in the same direction, and means for holding the clothes line taut when said arm is swung to a position exteriorly of the window casing.

2. In a clothes line support of the character described, an arm pivotally connected with a window casing and adapted to swing into and out of a window opening, pulleys for supporting a plurality of lines on the free end of said arm, spaced pulleys arranged on the hinged end of said arm, one of said last mentioned pulleys acting as a guide and the other as means for maintaining the line under tension, a pair of guiding pulleys, means for supporting said guiding pulleys on said casing, and a plurality of pulleys arranged an appreciable distance away from said casing for supporting and guiding the outer part of the line passing through said first mentioned pulleys.

3. In a clothes line support of the character described, a pivotally mounted supporting member adapted to swing through a window opening, a plurality of pulleys arranged on the free end of said arm for supporting different sections of a clothes line, a plurality of pulleys exteriorly of the window for supporting said clothes line, means for supporting said last mentioned pulleys, and means for guiding the various sections of said clothes line so that the outwardly moving parts will move in the same direction and at the same speed.

4. In a clothes line support of the charac-

ter described, an arm adapted to be connected to the casing of the window, a pulley supporting bar adapted to be connected to said window, guiding pulleys arranged on 5 said pulley supporting bar, pulleys arranged on the free end of said arm, an outside bar, and pulleys arranged on said outside bar, all of said pulleys being adapted to support and guide a clothes line doubled upon it- 10 self, whereby there will be two sections moving outwardly simultaneously while two adjacent sections move inwardly.

5. In a clothes line support of the character described, a swinging arm, a fixed bracket, a swinging bracket, a locking mem- 15

ber for locking the swinging bracket in a plurality of adjusted positions, a pulley adapted to be connected with each of said brackets for supporting sections of a clothes line, and pulleys arranged exterior of the 20 window casing for assisting in supporting said clothes line.

In testimony whereof I have signed my name to this specification in the presence of two subscribing witnesses.
